UNITED STATES PATENT OFFICE.

CHARLES CRAWFORD DAVIS, OF FENTON, MICHIGAN.

LOUD SPEAKER.

Application filed July 17, 1925. Serial No. 44,207.

This invention relates to devices for the reproduction of sound and more particularly loud speakers such as are used in connection with radio receivers wherein it is desirable that quality of tone should be preserved to the exclusion of noises or vibrations tending to interfere with the proper reproduction of sound, and especially is it desirable that such reproducers or loud speakers be free from periods of resonance such as will result in the setting up of sympathetic vibrations in the material of the reproducing medium or diaphragm which will be of an audible degree or frequency and consequently, be the cause of objectionable distortion of or interference, with the required sound reproduction.

It is, therefore, the object of this invention to produce a diaphragm construction which will practically eliminate the aforesaid objectionable features hitherto so common in sound amplifying forms or loud speakers in a very simple and highly efficient manner, the said invention further aiming to provide a diaphragm wherein vibrations impressed thereon will be truly reproduced, and wherein there will be no point of resonance which would set up a sympathetic vibration of high enough frequency to produce an audible sound, so that the only sounds produced by the diaphragm would be those resulting from the actual vibrations impressed upon the diaphragm.

The said invention further contemplates the impressing of vibrations on a diaphragm wherein tension as ordinarily provided is avoided, and wherein the vibrations are impressed upon the diaphragm in a direction parallel thereto instead of at right angles to the plane of the diaphragm as has been hitherto the common practice; and a still further object of the said invention is to provide for the suspending of a diaphragm from opposite edges so that it assumes the form of a depending loop or U-shape, upon one end of which the vibrations to be reproduced are impressed in the direction of the length of the diaphragm.

Still further objects subsidiary to or resulting from the aforesaid objects, or from the construction or operation of the invention as it may be carried into effect, will become apparent as the said invention is hereinafter further disclosed.

In carrying the said invention into effect, I may provide within a suitable framework

or housing a suspended needle or rod adapted to be vibrated in the direction of its length by means of a suitable vibration reproducing unit, and one or more diaphragms of fairly stiff paper or similar material attached at one end to an abutment carried by the said vibratory rod, and at the other end to a suitable support such as the said housing, the said diaphragms being of substantial area and of greater length than the distance between their points of attachment to the said support and to the said abutment, so that they will extend in the form of loops from their points of attachment. Consequently, ends of the diaphragms approximate to the vibratory rod will be practically parallel with the said rod, whereby the vibrations of the said rod will be impressed upon the parallelly extending adjacent ends of the diaphragms and impressed on the said diaphragms in a direction extending therealong. All of which is more particularly described and ascertained, by way of example, having reference to the accompanying drawing, wherein—

Figure 1 is a sectional elevation of a loud speaker embodying the said invention;

Figure 2 is a sectional elevation of the same, the section being taken at right angles to that shown in Figure 1;

Figure 3 is a plan of the same, part of the vibratory rod support being broken away for the sake of clarity of illustration; and

Figure 4 is a detail view of one of the diaphragms detached, and in a flat condition.

Similar characters of reference indicate similar parts in the several figures of the drawing.

1 indicates a box or framework which may have openings 2 and 3 provided at the sides thereof to permit greater freedom of passage of sound waves for the diaphragms, and 4 is a loud speaker unit, the details of which are not described herein, as it is of a well known construction and many different types of units may be utilized, the particular form of unit not being essential to the invention. The said unit has a vibratory member 5 to which is connected a vertically disposed vibratory rod or needle 6 which is suspended by a spring 7 at its upper end from an adjustable member 8 carried by a support 9 which extends from one side of the framework 1, 10 being a nut for effecting the adjustment of the said member 8. The spring 7 is of course of such a nature

that it does not itself have a resonant point tending to produce an audible sound when the device is in operation.

Securely mounted on the rod 6 is an abutment 11 comprising a pair of small blocks of wood or other suitable material, and 12 are diaphragms in the form of triangular pieces of stiff paper or other suitable material capable of vibrating in the desired manner, the smaller ends 13 of these diaphragms being secured to the outer vertical faces of the abutment 11 on opposite sides of the rod 6, and the broad ends 14 of the said diaphragms being secured such as by binding strips 15 and screws 16 to the upper inner margins of the framework 1.

These diaphragms are of substantially greater length than the distance between their points of attachment to the framework 1, and the abutment 11, so that they are bowed or looped downwardly as a consequence of which the inner ends 13 of the said diaphragms extend upwardly in a direction approaching parallelism with the axis of said rod 6, so that longitudinal vibration of the said rod as a result of the action of the vibratory unit will cause the abutment 11 to impress such vibration upon the ends 13 of the diaphragms 12 in a vertical direction, which is of course the direction of the disposition of such ends of the diaphragms. This is contrary to the usual method of impressing vibrations upon a diaphragm, the common practice being to impress such vibrations upon a diaphragm at right angles or at a substantial angle to its plane.

In the present instance, the inner ends of the diaphragm are exerting to some extent a downward pull on the abutment 11 in the direction of the length of the diaphragm at the point of its attachment, so that the vibrations may be said to be impressed upon such diaphragm in such direction, and they are transmitted through said diaphragm from their inner ends and set up vibratory motions in the diaphragm corresponding thereto without setting up resonant vibrations of an audible nature which would otherwise distort and reduce the quality of the sound reproduced by such diaphragms.

The invention is not limited to the number of diaphragms which may be utilized, as it will be obvious that these may be varied to suit requirements or desirability.

The provision for adjustment of the rod 6 is of course optional and may in many cases not be utilized especially where the vibratory unit 4 is of such nature that no such adjustment is required, but in many cases the adjustment of the vibratory element 5 is desirable, and it may be effected in the suggested manner.

The hanging nature of the diaphragms overcomes the tendency so strongly present in disk and similar diaphragms to assume a definite position of rest with consequent resonance when disturbed from such position, the position of rest in such hanging diaphragms varying with the respective positions of the supports of the diaphragm, so that as the inner ends of the diaphragms are raised and lowered by vibration the tendency of the diaphragm is simply to assume new positions of rest, agreeing with such raised and lowered position, the variations of which are however extremely slight.

Preferably the diaphragms are of such nature that there is practically no tension thereon other than that resulting from their own weight, and it is found that a loud speaker constructed in the manner described will reproduce both high and low notes without distortion and with great fidelity.

This invention may be developed within the scope of the following claim without departing from the essential features of the said invention, and it is desired that the specification and drawing be read as merely illustrative and not in a limiting sense, except as necessitated by the prior art.

What I claim is:—

In a sound reproducing device, a diaphragm support, a vibratory member, means resiliently supporting said vibratory member, means for effecting the vibration of said member, and a diaphragm suspended from opposite ends from said support and said vibratory rod.

In testimony whereof I affix my signature.

CHARLES CRAWFORD DAVIS.
